OUTLET BOX FOR AIR CONDITIONING SYSTEM

Bernard E. Curran, Sewickley, Pa., assignor to H. H. Robertson Company, Pittsburgh, Pa., a corporation of Pennsylvania

Filed Mar. 14, 1957, Ser. No. 646,038

7 Claims. (Cl. 98—38)

This invention relates to a novel outlet or sill box for use in an air distributing system and particularly in an air conditioning system wherein air of different condition is supplied to and mixed within the outlet or sill box.

One of the objects of the invention is to provide a novel construction of outlet or sill box for the purpose specified adapted to be used with advantage in muffling the sound of the air stream being discharged from the outlet or sill box.

A further and more specific object of the invention is to provide a novel outlet or sill box which is particularly designed for use in connection with an air conditioning system of the type in which two streams of differently conditioned air is supplied to the outlet or sill box to be mixed therein and discharged therefrom and wherein a major portion of the sound of the air streams is absorbed during the passage thereof through the sill box.

With these general objects in view and such others as may hereinafter appear, the invention consists in the outlet or sill box structure and in the various structures, arrangements and combinations of parts hereinafter described and particularly defined in the claims at the end of this specification.

In the drawings:

Fig. 1 is a diagrammatic plan view illustrating one portion of a floor of the air conditioning and building structure forming the subject matter of the Goemann Patent No. 2,729,429, dated January 3, 1956;

Fig. 2 is a detail partially in elevation and partially in section illustrating the present sill box connected to an air conducting cell of the structure shown in Fig. 1;

Fig. 3 is a vertical sectional view illustrating an outlet or sill box embodying the present invention which is erected upon two air conducting floor cells of the Goemann patent above referred to and from which air of different condition may be introduced into the sill box as will be described;

Fig. 4 is an enlarged sectional view of the outlet box shown in Fig. 3;

Fig. 5 is a sectional view of the outlet box showing a modified form of baffle unit;

Fig. 6 is a perspective view of a modified form of the baffle unit used in the present sill box as illustrated in Fig. 9;

Fig. 7 is a developed plan view of one-half of the blank used in producing the structure shown in Fig. 6 as will be described;

Fig. 8 is an enlarged sectional view of the outlet or sill box shown in Fig. 2; and

Fig. 9 is a vertical sectional view illustrating an outlet or sill box embodying the baffle unit shown in Fig. 8 which is erected upon two air conducting floor cells of the Goemann patent above referred to and from which air of different condition may be introduced into the sill box as will be described.

In general the invention contemplates a novel construction of outlet box for an air distributing system, and as illustrated therein, the outlet box may be used as a com-

2

ponent of a sill box or of a ceiling outlet unit in the air distributing system illustrated in the United States Patent to Goemann, No. 2,729,429, wherein air, and preferably conditioned air, may be distributed through a cellular metallic load supporting floor to be delivered to the present sill boxes or ceiling outlets in the manner described in such Goemann patent to which reference may be made.

Referring to the drawings, the present construction of sill box in the broader aspects of the invention comprises 10 a chamber 10, preferably of sheet metal, having an inlet opening 12 through which an air stream may be introduced into the sill box and an outlet opening 14 from which the air may be discharged into the room. In accordance with the present invention the interior walls of 15 the sill box may and preferably will be lined with sound absorbing material 15 preferably comprising hair of a thickness approximately one-quarter of an inch. In order to increase the sound absorbing efficiency of the outlet box structure provision is preferably made for suspending one 20 or more baffle members within the chamber. Preferably, the baffle or members may comprise a unitary structure 16 insertable through the opening 14 constituting the air outlet from the chamber and preferably supported by a flange 18 engaging the outer surface of the wall of the 25 chamber surrounding the discharge outlet. Preferably, the baffle members of the structure 16 may be arranged to cross one another at an angle and thereby deflect air through slots 19 therein in directions angular with respect to one another so as to thoroughly mix air streams emerging 30 through the slots into the trough-like portions 20 of the structure 16 prior to discharge of the mixed air through the outlet from the chamber.

In the air conditioning system illustrated in the Goemann patent, above referred to, it is desirable to provide 35 a structure of sill box having two inlet openings 12, 12A through which air of different condition may be introduced to within the sill box from air conducting cells 13, 13A of the cellular metal floor and through which air of different condition is supplied. For such a purpose the 40 sill box may comprise an elongated chamber having spaced inlet openings 12, 12A in the bottom wall thereof and a single elongated outlet 14 in the upper wall thereof. The present baffle structure may be suspended, as described, in the interior of the chamber and held in 45 operative position by engagement of flanged portions thereof with the outer wall of the chamber surrounding the outlet opening. In one form of the invention, as shown in Figs. 6-9, the baffle structure comprises a troughlike portion 20 and depending angularly disposed 50 baffles 16A, 16B, and one end portion of the baffle structure is provided with a surface having a series of slots 19 therein, and the surface is preferably sound absorbing as by a covering of hair of a thickness of approximately one-quarter of an inch. The baffle is suspended at an 55 angle directly across the mouth of one inlet opening to which air of one condition is being introduced so that as the air enters the interior of the chamber through the inlet opening 12 its direction is changed by the sound absorbing surface of the baffle and deflected against the interior of the sound absorbing surface of the adjacent portion of the interior of the chamber and thence through the slotted openings 19 into the troughlike mixing chamber immediately below the outlet opening 14. The second portion of the baffle structure is arranged to stand at 60 a similar angle but in the opposite direction as the first baffle so that air entering the second inlet 12A is deflected along the surface of the baffle angularly suspended across the mouth of the inlet and caused to engage and deflect from several walls of the adjacent portion of the chamber finally emerging through the slotted portion of the second baffle into the interior of the mixing chamber immediately below the outlet where the emerging streams 65

become thoroughly mixed prior to being discharged from the outlet or sill box.

In another form of the invention, as illustrated in Figs. 3 and 4, the baffle structure comprises a troughlike portion 22 suspended within the outlet or sill box and having its upper portion in communication with the sill box outlet 14. The troughlike portion 22 is provided with substantially straight parallel side walls 24, 26 and angularly disposed bottom walls 28, 30. The bottom walls 28, 30 are each provided with a plurality of spaced openings or slots 32 therein, and also the exterior surface thereof is covered with a layer of sound absorbing material 15, preferably sound absorbing hair approximately one-quarter of an inch thick. The baffle structure is preferably suspended within the chamber 10 of the sill box so as to present the apex of the angularly disposed bottom walls 28, 30 over the spaced inlet openings 12, 12A through which the differently conditioned air is introduced into the chamber 10. In practice a portion of the air directed into the interior of the chamber 10 through the inlet openings is deflected by the walls 28, 30 against the sound absorbing surface 15 of an adjacent portion of the interior of the chamber and thence through the slotted portions 32 into the troughlike mixing chamber 22. The air flowing into the mixing chamber 22 through the slots 32 in the walls 28, 30 emerges through the slots into the mixing chamber in a substantially crisscross pattern, and in this manner sufficient turbulence is created within the chamber, and the air is thoroughly mixed prior to its discharge from the outlet or sill box through the outlet opening 14.

In a still further form of the present invention illustrated in Fig. 5, the baffle structure comprises a troughlike portion 34 having substantially straight parallel side walls 36, 38 and a curved or arched bottom wall 40. The surface of the walls of the baffle structure is preferably covered by a layer of sound absorbing material 15, such as hair or other suitable material, and the curved bottom wall is provided with a plurality of spaced openings or slots 42 therein which may be similar to the openings illustrated in Fig. 3. The baffle structure is also adapted to be suspended within the chamber 10 of the sill box in the manner heretofore described in connection with Fig. 4, and the curved slotted bottom wall 40 is preferably disposed over the air inlets 12, 12A through which air of the same condition or differently conditioned air is directed into the chamber 10 from the air conducting cells 13, 13A as illustrated in Fig. 3. The air emerging from the inlets 12, 12A into chamber 10 is partially deflected by the curved bottom wall of the baffle structure against the sound absorbing walls of the chamber and then passes through the slots 42 into the troughlike mixing chamber 34. The slots 42 disposed in the curved wall 40 are arranged in angular relation to one another such that the air emerging through the slotted portions flows into the mixing chamber 34 in a substantially crisscross pattern and is thereby thoroughly mixed prior to being discharged from the sill box through the opening 14.

While the slotted openings in the lower walls of the baffle structure have been illustrated and described as comprising spaced slots, they may be of any desired shape.

From the foregoing description it will be observed that the described structure of sill or outlet box is relatively simple in construction; that the sound absorbing efficiency is higher; and that the baffle structure being detachably suspended on the sill box may be maintained in most efficient operating condition at minimum expense.

While the preferred embodiment of the invention has been illustrated and described it will be understood that the invention may be embodied in other forms within the scope of the following claims.

Having thus described the invention, what is claimed is:

1. An air outlet for an air distributing structure, comprising: a sill box having an air-receiving chamber and being provided with a plurality of air inlet openings for receiving differently conditioned air from a source of supply thereof and being provided with an air outlet opening for discharging said air to an area to be conditioned, said inlet and outlet openings being in different walls of said sill box, and an elongated baffle unit mounted in said sill box in alignment with said outlet opening, said baffle unit having end walls, and parallel side wall portions extending inwardly from adjacent said outlet opening and having outwardly diverging wall portions connected with the innermost part of said parallel wall portions, said parallel and diverging wall portions forming a mixing chamber in said baffle unit, said diverging wall portions having openings therein, at least a portion of the air stream entering said sill box chamber through the air inlet openings being deflected by a diverging wall portion toward a wall of said sill box chamber for subsequent discharge through the openings in said diverging wall portions into said mixing chamber to be discharged through the outlet opening.

2. An air outlet as defined in claim 1 in which the mixing chamber in the baffle unit is of a length at least equal to the combined length of said inlet openings.

3. An air outlet as defined in claim 2 in which the outlet opening is substantially coextensive in length with the length of the mixing chamber.

4. An air outlet as defined in claim 1 in which the baffle unit is inserted in the inlet opening and has peripheral flange portions supporting the same in said outlet opening.

5. An air outlet for an air distributing structure, comprising: a sill box having an air-receiving chamber and being provided with a plurality of air inlet openings for receiving differently conditioned air from a source of supply thereof and being provided with an air outlet opening for discharging said air to an area to be conditioned, said inlet and outlet openings being in opposite walls of said sill box, and an elongated baffle unit mounted in said sill box in alignment with said outlet opening, said baffle unit having end walls, and parallel side wall portions extending inwardly from adjacent said outlet opening and having outwardly diverging wall portions connected with the innermost part of said parallel wall portions, said parallel and diverging wall portions forming a mixing chamber in said baffle unit, said diverging wall portions having openings therein, at least a portion of the air stream entering said sill box chamber through the air inlet openings being deflected laterally by said diverging wall portions against the walls of said sill box chamber and thence through the openings in said diverging wall portions into said mixing chamber to be discharged through the outlet opening.

6. An air outlet as defined in claim 5 in which one of the diverging walls has an extension overlying a portion of one inlet opening and the other of the diverging walls has an extension overlying a portion of another inlet opening to provide a substantially cross flow pattern of the air within the mixing chamber.

7. An air outlet as defined in claim 6 in which the parallel wall portions, the diverging wall portions and their respective extensions are covered on the outer surface thereof with sound absorbing material.
